A. C. GAYNOR

PUSH BUTTON

Filed Jan. 19, 1924

34
BY ARTHUR C. GAYNOR.
Counselor at Law
ATTORNEY

UNITED STATES PATENT OFFICE.

ARTHUR C. GAYNOR, OF STRATFORD, CONNECTICUT.

PUSH BUTTON.

Application filed January 19, 1924. Serial No. 687,195.

To all whom it may concern:

Be it known that I, ARTHUR C. GAYNOR, a citizen of the United States, and a resident of Stratford, county of Fairfield, State of Connecticut, have invented certain new and useful Improvements in Push Buttons, of which the following is a specification.

This invention relates to a push button for electric circuits, particularly of the type used for electric bell and similar circuits.

In the ordinary type of push buttons, the button is made of a solid piece of insulating material loosely mounted in a suitable button opening in a housing and positioned to press a leaf spring contact member into contact with a stationary contact member as the button is pressed inwardly. In devices of this type and construction, the button is liable to be tilted when pressure is applied obliquely or to one side of the center of the button and the button may then fail to bring the contact pieces into effective contact, particularly as the device becomes worn with use. Devices of this construction, moreover, are of a bulky construction and are not well adapted to withstand the destructive action of the elements.

These defects are obviated by my present invention, an object of which is to provide a simple, strong, and compact push button, which may be easily assembled and is efficient and reliable in operation.

Another object of the invention is to provide, in devices of this type, contact members which make effective contact when the actuating push button is pressed in an inclined or tilted position on the contact pieces.

Other objects of the invention are to provide an improved support for the contact block of a push button, to provide an arrangement of push button, supporting recess for the button, and contact members that will permit an oblong button to be successfully employed, and to provide a hollow button and contact members therefor that will enable the device to be made compact and flat in construction.

With these and other objects in view, the invention comprises the push button de-

vice described and set forth in the following specification and claims.

The various features of the invention are illustrated in the accompanying drawings, in which:

Fig. 1 is a front or plan view of a push button device embodying my invention.

Fig. 2 is a section of the push button taken on line 2—2 of Fig. 1.

Fig. 3 is a bottom plan view of the push button.

Fig. 4 is a cross sectional view of the push button, taken on the line 4—4 of Fig. 1.

Fig. 5 is an enlarged sectional view, substantially on line 2—2 of Fig. 1, of a portion of the device when the contacts are depressed by the push button tilted to one side.

Fig. 6 is a view of a portion of the device similar to that of Fig. 5 but showing the button tilted in the opposite direction.

Fig. 7 is a detail perspective view of a button housing forming a part of the device.

Fig. 8 is a perspective bottom view of the button member of the device.

Fig. 9 is a perspective view of an insulating member adapted to be mounted in the button, and

Fig. 10 is a perspective view of a contact supporting block for use in the apparatus.

In my present invention, the contact terminals are mounted on a terminal block, preferably by means of the binding screws, in such a position as to overlap at the portions where contact is to be made. The upper of these contacts is sprung upwardly out of contact with the lower and its upper surface is rounded and presses upwardly against the under surface of a push button, holding the push button in its outward position in a guiding recess. This push button is preferably hollow to enable the entire structure to be made flat, the upper part of the upper contact terminal being received in the hollow portion of the button. When any portion of the button is depressed, it engages the upper surface of the upper contact terminal and presses it against the lower terminal, thus enabling an elongated button to be used. The terminal block is supported by a pair of

standards struck inwardly from the opening in which the push button is guided, thus enabling a compact, strong, structure to be obtained.

5 Referring more particularly to the accompanying drawings, a pair of contact terminals 12 and 14 are mounted on a terminal block 16 and connected to wires 18 of an electric circuit by means of a pair of binding 10 screws 20 and 22. The terminal block 16 with its associated elements is supported in a housing 24 by means of a pair of standards 26 and 28 which are stamped rearwardly from the side edges of a button recess or hole 15 30 and fit into and engage recesses 32 and 34 in the side edges of the terminal block 16. As indicated most clearly in Fig. 7, each standard has a wide portion 36 adjacent the edge of the opening 30 on the inner or rear 20 edges of which rests the forward face of the terminal block 16, a narrow or neck portion 38 which fits into the recess 32 or 34 and a wider end portion which is bent over the lower or rear edge of the block 16 in a pair 25 of claws 40 to secure the block in position.

As indicated in the example shown in the drawings, the opening 30 is preferably elongated, having a pair of parallel side edges 42 and 43 and symmetrical rounded ends 44 30 and 45, and the standards 26 and 28 are formed by slitting the metal through which the opening 30 is to be stamped along its longer axis, butting the metal into the required form and bending inwardly at right 35 angles to the surface of the housing. The housing 24 may be made or stamped integral with an escutcheon 46 or may be mounted thereon by means of lugs 48 bent under the edge of a hole 50 covered by the button housing. The escutcheon may be mounted on a 40 supporting surface 52 by means of a pair of screws 53 or other suitable means.

The terminal contact 14 is mounted on the terminal block 16 with a portion resting 45 against the front face of the block then bent to fit in a recess 54 in the lower end of the block and continuing rearwardly and bent to form a flat portion 56 resting against the rear face of the block. The terminal is secured to the block by means of the binding 50 screw 22 which passes through an opening in the flat portion 56 of the terminal and extends into or through an opening 58 in the lower part of the block. The front portion 55 of the terminal is rounded forwardly from the front face of the terminal block 16 forming a forwardly rounded contact portion 60.

The other contact terminal 12 is similarly mounted on the block 16 with a portion fitted in a recess 62 at the upper end of the block 16 and continuing in a portion 64 on the rear face of the block and secured thereto by means of the binding screw 20 mounted in an opening 66 in the upper portion 65 of the block. The forward portion of

the terminal is also bent into a forwardly rounded portion 68 immediately in front of and overlapping the portion 60 of the terminal 14 and is normally sprung forwardly out of contact with the portion 60. When 70 pressure is applied to any portion of the front face of the portion 68, however, it is depressed into contact with the portion 60 of the lower terminal 14, swinging about its support or junction on the block 16 and being thus positively positioned relative to the lower terminal so that pressure applied to any portion of its rounded projecting portion will bring it into effective contact with the contact 14.

In its forwardly sprung position, the contact 12 presses against the inner surface of a hollow metallic push button 70 being protected from direct contact with the metallic surface of the button by means of an intervening layer of insulating material 72. The button is formed of a flat forward portion 74 against the inner surface of which the contact 12 presses and a rearwardly extending flange 76 extending about the entire edge of the button. The button is normally pressed outwardly by the contact 12 until lugs 78 extending outwardly from the rear edges of the flange 76 are brought up against the rear surface of the housing 24, there being preferably four or more of the lugs 78, so that, should the button be pressed rearwardly at one end or edge, it may pivot about the opposite pair of lugs.

The button will thus depress or push the contact terminal 12 into contact with the contact terminal 14 as the button is pushed straight backwardly or tilted about a pair of the lugs 78, as illustrated in Figs. 5 and 6, since the contact 12 swings into contact 100 making position when any portion of the rounded surface 68 is pressed backwardly from any angle. The button may therefore be made of an elongated shape corresponding to the shape of the opening or recess 30 inasmuch as the contact terminals will be brought into contact even though the button be depressed or tilted about one end. The button is accordingly formed with a pair of straight sides 80 and 81 corresponding to the sides 42 and 43 of the hole 30 and with rounded ends 82 and 83 corresponding to the rounded ends 44 and 45 of the opening 30.

An elongated button of this type which will operate the contacts successfully when any portion of its surface is pushed is very desirable as it presents a pleasing and attractive appearance and is more easily actuated. The hollow construction is also desirable in this connection as it enables the structure as a whole to be made more compact and flat in appearance and less likely to be injured. The button may be made of any desired material but metal is generally 120 125 130

desired as it withstands the action of the weather and of the elements without injury or deterioration in appearance.

Having described the invention, what I claim and desire to secure by Letters Patent is:

1. A device of the type described which comprises, a housing having an opening for a push button, a pair of supports struck up 10 from said housing at the edge of said opening and a terminal block engaged between and supported by said supports.
2. A device of the type described which comprises, a housing for a push button having 15 a recess, a pair of supports struck up from the edges of said recess, a terminal block supported by said supports, said supports having an edge on which the front face of said block rests, a narrowed portion 20 extending through a recess in said block, and a claw portion engaging the rear of said block.
3. A device of the type described which comprises a push button, a housing having

a recess for said button and a pair of supports struck in from said recess, a terminal block supported between and by said supports, a pair of terminals mounted on said block and having overlapping contact portions, one of said terminals having an outwardly rounded portion and being sprung outwardly to bring said rounded portion against the inner surface of said button. 25 30

4. A device of the type described which comprises, a hollow push button, a housing having a recess for said button and a pair of supports struck rearwardly from the edges of said recess, a terminal block supported between and by said supports, a pair of terminals mounted on said block and 35 40 having outwardly rounded overlapping contact portions, one of said terminals being sprung forwardly to bring said rounded portion against the inner surface of said button. 45

ARTHUR C. GAYNOR.
